[57] CLAIM

The ornamental design for a chair, as shown and described.

DESCRIPTION

FIG. 1 is a front perspective view of the chair showing my new design;

FIG. 2 is a left side elevational view, the right side elevational view being a mirror image thereof;

FIG. 3 is a bottom plan view;

FIG. 4 is a top plan view;

FIG. 5 is a front elevational view;

FIG. 6 is a rear elevational view thereof; and

FIG. 7 is a front perspective view of a second embodiment of the chair showing my new design.
